Fig. 6

Fig. 8

Fig. 7

FIG. 1 is a perspective view of a telephone substation apparatus showing one embodiment of our new design;

FIG. 2 is a top plan view of the form shown in FIG. 1;

FIG. 3 is a side elevational view of the form shown in FIG. 1, the opposite side being substantially similar in form;

FIG. 4 is a perspective view of a telephone substation apparatus showing another embodiment of our design;

FIG. 5 is a top plan view of the form shown in FIG. 4;

FIG. 6 is a side elevational view of the form shown in FIG. 4, the opposite side being substantially similar in form;

FIG. 7 is a rear elevation of the form illustrated in FIGS. 1, 2 and 3;

FIG. 8 is a rear elevation of the form illustrated in FIGS. 4, 5 and 6.

We claim:

The ornamental design of a telephone substation apparatus, substantially as shown and described.
